UNITED STATES PATENT OFFICE.

DAVID A. LEE, OF CENTERVILLE, IOWA.

COALING SYSTEM.

1,048,325.

Specification of Letters Patent. Patented Dec. 24, 1912.

Application filed April 3, 1912. Serial No. 688,241.

To all whom it may concern:

Be it known that I, DAVID A. LEE, a citizen of the United States, residing at Centerville, in the county of Appanoose and State of Iowa, have invented certain new and useful Improvements in Coaling Systems, of which the following is a specification, reference being had therein to the accompanying drawing.

10 This invention relates to coaling systems for railroads using steam locomotives, and the principal object of the invention is to provide an improved device whereby the motion of the locomotive along the track 15 will serve to elevate the coal and deposit the same in the tender.

With the above and other objects in view, the invention consists in general in certain novel details of construction and combinations 20 of parts hereinafter fully described, illustrated in the accompanying drawings, and specifically claimed.

In the accompanying drawings like characters of reference indicate like parts in the 25 several views, and:—Figure 1 is a perspective view of a device constructed in accordance with this invention, the tender of the locomotive being indicated by dotted lines. Fig. 2 is a vertical median section through 30 such device. Fig. 3 is a plan view thereof. Fig. 4 is an enlarged detail view of such hooks used in connection with the dumping mechanism. Fig. 5 is a side elevation of a portion of the locomotive tender equipped 35 for use in connection with this device. Fig. 6 is a detail view of the lower part of this device showing the same used in connection with an automatic feed hopper, the door of the hopper being closed. Fig. 7 is a similar 40 detail showing the bucket in lowered position with the door of the hopper open. Fig. 8 is a plan view of this portion of the device.

This invention includes a tower constructed of suitable structural material, and is provided with corner posts 10 tied together at intervals by means of braces 11, and having their tops connected by bars 12. The tower is furthermore braced with diagonal members 13 and is equipped with L-shaped guides 14, which extend diagonally from the rear to the front. At the upper end of these guides 14 there is provided on the front members 10 suitable eyes 15 arranged for the reception of a rod 16. Extending diagonally across the top of the

tower is a pair of angle braces 17 between which are mounted guide pulleys 18. Adjacent the bottom of one of the members 10 is a third guide pulley 19 and positioned in spaced relation to the tower is a pulley 20. Slidably mounted in the guides 14 is a bucket 21, which has hinged to its bottom a bail 22, the latter being held by suitable eyes 23. Secured to the bight of the bail 22 is a hoisting rope or cable 24, which is trained over the guide pulleys 18 under the pulley 19, and around the pulley 20. Upon the end of this cable 24 there is provided a hook 25 which is arranged to engage an eye 26 secured to the side of the engine tender 27.

On what may be termed the front of the bucket 21 there is provided a plurality of eyes 28 to each of which is connected a hook 29, the bill whereof faces outward so that as the bucket is drawn up by the guides these hooks will engage the bar 16. In order to prevent the bucket being drawn to too great a height a suitable foundation 30 is made adjacent the track 31 and in this foundation is sunk an eye-bolt 32 which is engaged by one end of a chain 33; the other end being connected to the hook 25.

In the operation of the device the bucket 35 is loaded with coal in its lowered position. The hook 25 is engaged with the eye 26 on the tender and the engine moved forward. Now as the engine moves forward along the track the rope is drawn upon and causes the 40 bucket to move upward on the guides 14. When the hooks come in contact with the bar 16 further movement of the bucket bodily is prevented, but as the engine proceeds the bottom of the bucket is drawn upward so that the same revolves about the bar 16 and the load of coal is dumped into the tender. If by any chance the engineer fails to stop the engine at the proper time the chain 33 will prevent too great movement.

With this type of bucket it is preferred to use a charging hopper of novel construction now to be described. At the rear of the tower there is provided a track the rails whereof are indicated at 33' for coal cars and this track extends over a hopper having a downwardly inclined bottom 34 and slanting sides, and a rear end, as indicated at 35 and 36, respectively. The front of the hopper is preferably disposed vertically although the same may be inclined outwardly

if found desirable, this front being indicated at 37 and it is to be noted that beneath the front 37 there is provided a delivery opening 38. Extending across said 5 delivery opening 38 is a swinging door 39 arranged to constitute a delivery chute when open. This door is hinged intermediate its top and bottom edges as indicated at 40 and the lower part of the door projects below the bottom of the hopper so that when 10 the door is open it assumes the position shown in Fig. 7, this lower part contacting with the bottom of the hopper to retain it in the said position. The hopper is normally 15 raised from the ground and supported on suitable standards 41 and at the bottom of the tower there is a well 42 wherein the bucket rests when in its lowermost position so that the bucket is beneath the mouth of 20 the hopper. On the underside of the hopper is secured a spring latch 43 provided with a shoulder 44 so arranged that when the door 39 is closed the lower end thereof 25 will engage against this shoulder and hold the door in its closed position until released.

For the purpose of releasing the door the spring latch 43 is provided with a downwardly extending end 45 against which the 30 rear of the bucket 21 is adapted to contact when in its lowermost position. In the operation of this part of the device as the bucket comes down empty the rear wall thereof strikes the end 45 and depresses the 35 spring latch 43, thus releasing the door and permitting it to assume the position shown in Fig. 7. After the bucket has been filled and starts on its upward journey the upper end of the rear wall strikes the door 39 and 40 forces it to closed position at the same time that the spring latch is released from engagement with said rear wall so that it is in position to hold the door closed when the same is closed by the upward movement of 45 said bucket.

There has thus been provided a simple and efficient device of the kind described, and for the purpose specified.

It is obvious that many minor changes 50 may be made in the form and construction of the invention without departing from the

material principles thereof, and it is therefore not wished to confine the invention to the exact form herein shown and described, but it is wished to include all such as properly come within the scope claimed. 55

Having thus described the invention what I claim as new is:—

1. In a device of the kind described, a skeleton frame constituting a tower, a bar 60 extending across the front of said tower, inclined guide-ways leading upward from the back of the tower to points on the front of the tower below the top, a bucket slidably mounted in said guide-ways, hooks on said 65 bucket adapted to engage said bar, guide-pulleys carried by said tower, a guide pulley located in spaced relation to the tower, a bail secured to the bottom of said bucket, a rope led over said guide pulleys and provided 70 at one end with a hook adapted for engagement with a portion of a moving car, the other end of said rope being secured to said bail, and a chain having one end secured to a fixed object and the other end secured 75 to said hook.

2. In a device of the character described, a guide-way, a bucket movable within said guide way, a hopper adjacent the bottom of said guide way, said hopper being spaced 80 above said bottom and to the rear thereof, said hopper being provided with a front wall having a door opening therein, a door plate hinged intermediate its ends at the lower edge of said opening, the lower part 85 of said plate extending beneath said hopper and being arranged to contact with the underside of the hopper when opened, a spring latch having one end secured beneath said hopper and being provided with a shoulder 90 portion arranged to engage the lower edge of the door plate when the latter is closed to retain the same in closed position, and a projecting end on said latch adapted for engagement with the rear wall of the bucket 95 when the latter is lowered.

In testimony whereof I hereunto affix my signature in presence of two witnesses.

DAVID A. LEE.
